US00D829975S

(12) **United States Design Patent** (10) **Patent No.:** **US D829,975 S**
(45) **Date of Patent:** **** Oct. 2, 2018**

(54) **ELECTRONIC CIGARETTE**

(71) Applicant: **Altria Client Services LLC**,
Richmond, VA (US)

(72) Inventor: **Mitchell Stone**, Staffordshire (GB)

(73) Assignee: **Altria Client Services LLC**,
Richmond, VA (US)

(**) Term: **15 Years**

(21) Appl. No.: **29/592,186**

(22) Filed: **Jan. 27, 2017**

(30) **Foreign Application Priority Data**

Jul. 31, 2016 (EM) 003325349-0001
Jul. 31, 2016 (EM) 003325349-0002

(57) **CLAIM**

The ornamental design for an electronic cigarette, as shown and described.

DESCRIPTION

FIG. 1 is a perspective view of an electronic cigarette; FIG. 2 is a front view of the electronic cigarette; FIG. 3 is a rear view of the electronic cigarette; FIG. 4 is a left side view of the electronic cigarette; FIG. 5 is a right side view of the electronic cigarette; FIG. 6 is a top view of the electronic cigarette; and, FIG. 7 is a bottom view of the electronic cigarette. In the drawings, the broken lines depict environmental subject matter only and form no part of the claimed design.

1 Claim, 7 Drawing Sheets
